TIMING RELAY

Kolman Riesz, Gillette, N. J., assignor to Westinghouse Electric Corporation, East Pittsburgh, Pa., a corporation of Pennsylvania

Application May 5, 1950, Serial No. 160,120

3 Claims. (Cl. 200—37)

1

My invention relates to the mechanical structural design of a timing-relay element, such as is useful in the backup relaying part of the high-speed protective-relay system shown in Goldsborough's Patents 1,934,662 and 1,934,665 of November 7, 1933. Such a relay comprises (usually) two adjustable stationary contact-members, which are adjustable to different points along a 180° arc, and a movable contact-arm which moves over this arc, so as to make contact with first one and then the other of the two stationary contact-members, being driven by an electric motor through suitable reduction-gearing.

The principal object of my present invention is to provide a new assembly, including the arcuate guide or holder for the two adjustable stationary contact members, and a novel spring-lever design for performing the double function of holding the movable contact members in fixed relation with respect to the arcuate guide-member of the frame, and also as a fixed radial distance from the axis of the movable contact-arm of the relay.

More broadly stated, it is an object of my invention to provide a timing-relay assembly such that, once the moving contact is set for proper engagement with either one of the adjustable stationary contact members, the movable contact is always thereafter in a definite relation, radially and axially, to the two adjustable stationary contacts, regardless of the positions of the adjustable stationary contacts.

With the foregoing and other objects in view, my invention consists in the structures, combinations, assemblies, parts, and methods of design and operation, hereinafter described and claimed, and illustrated in the accompanying drawing, wherein:

Figure 1 is a top plan view of a simplified version of a preferred form of embodiment of a timing relay embodying my invention;

Fig. 2 is a side elevational view of just the frame member;

Fig. 3 is a front elevational view of the timing relay which is shown in Fig. 1;

Fig. 4 is a top plan view of one of the adjustable contact members, with the two contact strips shown in section;

Fig. 5 is an end elevational view of the adjustable contact member shown in Fig. 4; and

Figs. 6 and 7 are plan and elevational views, respectively, of one of the spring lever arms.

As shown in Figs. 1, 2 and 3, the illustrated timing relay is built upon a metal frame 7 having a vertical back-plate 8, a small horizontal top

flange 9, and a larger horizontal bottom flange 10 which is arcuate in peripheral contour, and which has a semi-circular arcuate slot 12 cut therein, so as to leave an arcuate supporting-part 13 between the arcuate slot 12 and the arcuate peripheral edge of the lower horizontal flange 10. Secured to the top surface of the arcuate support-member 13 is a thin calibrated arcuate dial 14, which is illustrated as being calibrated up to 180 cycles in ten-cycle steps.

A rotatable vertical main shaft 15 is disposed with its ends supported by bearings in the top and bottom plates 9 and 10 of the frame, so that it stands at the center of both the arcuate slot 12 and the arcuate guide 13 of the lower flange of the frame-member. Clamped at an axially adjustable height on the main shaft 15 is a movable contact-arm 16 which terminates in a pin 17 on which is loosely mounted a metallic contact-roller 18 having a bore 19 which is considerably larger than the pin 17 on which this contact-roller is supported. The main vertical shaft 15 is provided with a gear 21 which is driven by a pinion 22 on a parallel auxiliary shaft 23, which is also provided with a gear 24 which is driven by a pinion 25 on a motor-shaft 26, which is indicated by a diagrammatic representation of an electric motor M. This moving-contact assembly, including the drive-means therefor, is old.

According to my present invention, I provide one, and preferably two, adjustable stationary contact assemblies 31 and 32 of novel form and mounting. As the two adjustable stationary contact members 31 and 32 are identical, except for right and left-hand parts, a description of one will suffice for both.

The adjustable stationary contact assembly 31, according to my invention, comprises essentially a mold 33 of insulating material, which is specially shaped so as to have an upper part 34 which extends up through the arcuate slot 12, and also extends above said arcuate slot, so that the top of the mold lies a short distance below the level of the contact-roller 18. Below the upper part 34 of the insulating mold 33, there is an enlarged flange 35 which extends radially outwardly and inwardly, on both sides of the arcuate slot 12 of the stationary frame. As shown in Figs. 3, 4 and 5, the top surface of this flange 35 is provided with three elevated protuberances 36, 37 and 38 which provide a three-point support for engaging the under-surface of the horizontal arcuate flange 10 of the stationary support, so as to prevent the possibility of any wobbling of the stationary-

contact mold 33 when it is pressed up against the support, as will be subsequently described.

Extending vertically upwardly through the insulating mold 33 of each of the adjustable stationary contact members is a pair of spaced parallel tangentially directed slots or holes 41 and 42 (Fig. 4), for receiving the two silver contact strips 43 and 44. The silver strips are provided with rounded arrow-headed tops 45 which are adapted to be bridged by the contact-roller 18 when the contact-arm 16 moves over these silver contact-strips. The contact-strips are preferably inserted into the respective slots 41 and 42 from the top, and when they have been pushed down into position, their bottom ends may be bent over, as shown in Fig. 3, to lock the strips in place. For convenience in molding, instead of molding two narrow holes 41 and 42 for these contact-strips, the insulating mold 33 is conveniently provided with one or more large centrally disposed holes 48 which have enlarged ends which provide the slots 41 and 42 for holding the respective contact-strips 43 and 44 in place.

In accordance with my present invention, the enlarged lower flange-portions 35 of the insulating molds 33 are pressed upwardly against the underside of the arcuate horizontal flange 10 of the frame, by means of a pair of special springs 51 and 52, which are preferably substantially identical, except for right and left-hand construction. Thus, as shown in Fig. 6, the inner end of the spring 51 has a pivot-hole 52' which is pivotally mounted upon the lower bearing 53 for the main vertical shaft 15, underneath the lower flange 10 of the frame. As shown in Fig. 7, the spring 51 then has a downwardly stepped portion 54, close to the pivot-hole 52', and a main horizontally extending portion 55, which terminates in an upwardly bent hook 56 which bends over to engage the top of the peripheral portion of the arcuate dial 14.

As shown in Fig. 6, the main horizontal portion 55 of the spring 51 is provided with a hole or notches 57 and 58 for engaging a suitable downwardly extending protuberance 59 (Fig. 5) extending below the horizontal flange 35 of the insulating mold 33, so as to lockingly engage this mold and hold it in position radially with respect to the center-line of the main shaft 15 of the relay. The thickness of the mold-flange 35, above and surrounding this downwardly projecting protuberance 59, is sufficiently great so that the spring 51 is bowed downwardly thereby, thus causing the spring to exert an upward pressure on the mold, for frictionally holding its three supporting-points 36, 37 and 38 upwardly against the bottom flange 10 of the frame. This construction thus holds the adjustable contact assembly against wobbling, it vertically fixes the position of the adjustable contact assembly, it maintains the radial spacing between said adjustable contact assembly and the main shaft 15 of the relay, and it frictionally holds the adjustable contact assembly in whatever position it is placed in, according to the desired timing-adjustment of the relay.

As shown in Figs. 1 and 4, the outer periphery of the upper portion 34 of the mold may be provided with a suitable mark 61 for cooperating with the time-scale which is marked on the arcuate dial 14.

To enable my two adjustable stationary contact members 31 and 32 to be assembled and disassembled, I provide a special construction of the lower horizontal arcuate flange 10 of the

frame, and the arcuate dial 14. Thus, as shown in Fig. 1, I provide, in these parts, a peripheral notch 62 ahead of the zero position, and another peripheral notch 63 after the last position, in order to allow the release of the spring-tension and the easy removal of the stationary contact assemblies 31 and 32 for inspection. These notches 62 and 63 permit the hooked ends 56 of the respective springs 51 and 52 to be moved downwardly through these notches, so that the central portion 55 of the spring can be disengaged from the downwardly extending protuberance 59 of the insulating mold 33, thus permitting the parts to be disassembled, and conversely permitting their assembly again.

From the foregoing description and explanation, taken in conjunction with the drawings, it will be clear that I have provided an extremely strong and simple structure, which is self-aligning against horizontal warping or vertical tilting, which is simultaneously frictionally held in adjusted position, at its adjusted point circumferentially around the arcuate dial 14, and is also radially fixed at a fixed radius from the axis of the rotating arm 16. The vertical height of the top contact-points 45 of the contact-strips 43 and 44 is always fixed at a constant value with respect to the bottom surface of the arcuate horizontal flange 10 of the frame, and this bottom flange-surface is made with the necessary true-ness to be exactly in a horizontal plane at right angles to the vertical main shaft 15, so that, once the vertical height of the movable arm 13 has been properly adjusted, on the vertical shaft 15, so that the contact-roller 18 will make proper bridging-contact with the two contact-strips of either adjustable stationary contact assembly, then the proper bridging contact will be assured, for all arcuate positions of both of the stationary contact assemblies.

While I have shown and described a simplified version of my timing relay, in sufficient detail to explain its essential novel parts, it will be understood that certain parts and refinements have been omitted for the sake of simplicity, and as having nothing to do with the innovations which I have introduced in the relay. I wish it to be understood, therefore, that various changes may be made, in the way of adding auxiliary parts and features, and the substitution of equivalents, without departing from the essential spirit of my invention; and I desire that the appended claims shall be accorded the broadest construction consistent with their language.

I claim as my invention:

1. A timing-relay structure comprising: a frame having a vertical back-plate, a small horizontal top flange, and a larger horizontal bottom flange which is arcuate in peripheral contour, and which has a semi-circular arcuate slot therein; a rotatable vertical main shaft; bearings for supporting the ends of said main shaft in the top and bottom plates of the frame, so that said main shaft stands at the center of both the arcuate slot and the arcuate periphery of the lower flange of the frame; a movable contact-arm secured at a predetermined height on said main shaft; one or more adjustable stationary contact assemblies comprising a mold of insulating material and one or more contact-strips extending vertically through the mold, said mold having an upper part which extends up through the arcuate slot so that the top of the mold lies a short distance below the level of the contact-arm, said mold having an enlarged flange which engages

the bottom surface of the bottom flange of the frame, on both sides of said arcuate slot, said mold further having a downwardly projecting protuberance; and a spring for each stationary contact-assembly, said spring being pivotally mounted on the lower bearing for the main shaft, underneath the bottom flange of the frame, said spring having a hooked end which extends over the top of the arcuate periphery of said bottom flange, and said spring having a downwardly bowed intermediate portion which interlockingly engages said downward protuberance of said mold.

2. The invention as defined in claim 1, characterized by said bottom flange of said frame having a peripheral notch or notches which facilitate assembly and disassembly of said hooked end of the spring or springs.

3. The invention as defined in claim 1, characterized by said enlarged flange of the mold having three elevated protuberances for providing a three-point support for engaging the underside of the bottom flange of the frame.
